(57) **CLAIM**

The ornamental design for an aerial support tie, as shown
and described.

DESCRIPTION

FIG. 1 is a perspective view of an aerial support tie according
to the present invention.

FIG. 2 is a left side elevation view of the embodiment of
FIG. 1.

FIG. 3 is a right side elevation view of the embodiment of
FIG. 1.

FIG. 4 is a top plan view of the embodiment of FIG. 1.

FIG. 5 is a bottom plan view of the embodiment of FIG. 1.

FIG. 6 is a front elevation view of the embodiment of FIG.
1.

FIG. 7 is a rear elevation view of the embodiment of FIG.
1.

FIG. 8 is a perspective view of a second embodiment of an
aerial support tie according to the present invention.

FIG. 9 is a left side elevation view of the embodiment of
FIG. 8.

FIG. 10 is a right side elevation view of the embodiment of
FIG. 8.

FIG. 11 is a top plan view of the embodiment of FIG. 8.

FIG. 12 is a bottom plan view of the embodiment of FIG. 8.

FIG. 13 is a front elevation view of the embodiment of FIG.
8; and,

FIG. 14 is a rear elevation view of the embodiment of FIG.
8.

The broken lines represent portions of the structure that
forms no part of the claim.
